(57) **CLAIM**

I claim the ornamental design for a combined waist and hip exercising apparatus, as shown and described.

DESCRIPTION

FIG. 1 is a perspective view of a combined waist and hip exercising apparatus showing my new design;

FIG. 2 is a front view thereof;

FIG. 3 is a right side view thereof;

FIG. 4 is a left side view thereof;

FIG. 5 is a rear view thereof;

FIG. 6 is a top plan view thereof; and,

FIG. 7 is a bottom plan view thereof, where those portions of the design indicated by broken lines form no part of the claimed design.

1 Claim, 6 Drawing Sheets

FIG. 1

FIG. 6

FIG. 7
